(Cl. D58—8)

FIG.1

The side not shown is the same as the side shown.

The mid-section of the bottle is circular in transverse cross-section. The closed elongated loops on the tapered portions extending from the ends of the circular mid-section are relieved areas.

I claim:

The ornamental design for a bottle, substantially as shown and described.
